ABSTRACT

This invention relates to improvement on a device for separating a concrete pole and the like from a mold frame and respective parts of said device, which comprise providing an extruding device having an oil pressure jack at one end of the mold frame and a pulling-out device having a clamp trolley at the other end of said mold frame as a device for separating a concrete product such as a concrete pole or the like which has been subjected to centrifugal clamping and steam curing in the mold frame having a cut-into-two type circular section, after clamp bolts at one side of aforesaid mold frame have been released, extruding the content at a predetermined dimension by the aforesaid extruding device, and then clamping to pull out the content by said pulling-out device thereby to place the content on a roller.

**DEVICE FOR SEPARATING CONCRETE POLE
AND THE LIKE FROM MOLD FRAME**

SUMMARY OF THE INVENTION

This invention relates to a device for separating concrete poles, concrete piles and the like concrete products from the mold frame after molding.

In the manufacture of concrete poles and the like, heretofore there have been carried out such operations, by use of a mold frame assembly of a cut-into-two circular section, comprising the steps of firstly applying or spreading a mold releasing agent on the inner peripheral surfaces of both upper and lower mold frames, which contact the concrete, then installing a required reinforced cage in the lower mold frame, thereafter filling a required amount of the concrete in said cage, covering the upper mold frame on the lower frame, and clamping with bolt the flange parts of said mold frames to form an integral body, clamping the concrete by a centrifugal method, a vibration method or the like, hardening the concrete by steam curing thereby to complete molding, and releasing the product from the mold frame.

In the conventional method, however, in order to release the product from the mold frame, bolts of the flange are all removed and the upper mold frame is removed by a crane operation, then the product concrete pole is taken out by ball hanging of wire. Thereafter, since operations are repeated, aforesaid clamping of clamp bolts and releasing thereof require many skilled workhands and, in addition, labor therefor is heavy, the operational efficiency is inferior and it is not adapted for the flow process, and further the operation involves dangers.

The present invention relates to a device for releasing the products such as concrete poles and the like from the mold frame. A first object of the present invention resides in that a gap is produced between the concrete product and the upper mold frame by merely releasing clamp bolts at one side without removing all the clamp bolts for the mold frame, and thereafter a concrete pole or the like is extruded at its one end and pulled out at another end, and thus released from the mold frame, whereby the operations can be automatically carried out by use of a motive power, a troublesome clamp bolt removing operation is unnecessary, and hence the operation is simplified thereby to improve the operational efficiency.

A second object of the present invention resides in that the product such as concrete pole or the like which has been partly extruded from the mold frame by means of an oil pressure jack is clamped, the toggle effect of clamp click is utilized upon causing a clamp trolley to travel thereby to make the clamp operation accurate, the concrete product is pulled out on the roller with the use of clamp trolley, whereby mold-releasing can be carried out only by the operation on a plane and use of crane is not necessary, thus the safety and the efficiency of the operation being promoted.

Other objects and features of the present invention will be more apparent from a few following examples embodying the present invention as described in conjunction with drawings.

BRIEF DESCRIPTION OF THE DRAWINGS

The accompanying drawings show a few examples embodying the present invention, in which;

5 FIG. 1 is a front elevation showing the outline of the entire device according to the invention;

FIG. 2 is a side elevation showing the detail of an extruding device;

FIG. 3 is a front elevation partly showing the same;

10 FIG. 4 is a side elevation showing the essential part of the same;

FIG. 5 is a side elevation showing the detail of a pulling-out device;

15 FIG. 6 is a front elevation partly showing the same;

FIG. 7 is a plane view partly showing the same;

FIG. 8 is a plane view showing the other example of the pulling-out device, partly omitted; and

20 FIG. 9 is a front elevation partly showing the same.

DETAILED DESCRIPTION OF THE INVENTION

FIG. 1 shows the outline of the entire device according to the present invention, in which reference numeral 11 designates a concrete pole placed on a V block 13 for mold releasing after it has been subjected to centrifugal clamping and steam curing within the mold frame 12 having a cut-into-two type circular section. After a number of clamping bolts on one side at the flange part of said mold frame 12 have been released, the tip end of the concrete pole 11 fitted within the mold frame 12 is extruded about 50cm by means of an extruding device A having an oil pressure jack as will be described hereinbelow, and, on the other hand, the bottom end of the concrete pole 11 is clamped and pulled out by means of a pulling-out device B having a clamp trolley as will be mentioned below, and the concrete pole is placed on a position-fixed roller 14 as shown by imaginary line.

FIGS. 2, 3 and 4 respectively show the detail of the extruding device, in which reference numeral 15 designates an oil jack mounted on a trolley 16 in a freely vertically movable manner as will be mentioned below, and three clicks 20 are attached to said jack through a cam 18 fitted with an operating handle 17a and a cam sleeve 19. That is, a supporting frame 21 is fixed to the trolley 16 and an accepting base 24 for a screw rod 23 which ascends and descends by the operation of a handle 22 is mounted on said supporting frame 21. At the upper end of said screw rod 23 there is fixed a holding ring 25 outwardly fitting and supporting the oil pressure jack 15. The click 20 screwed with a bolt 26 at its base end comes into contact with the surface of the cam 18, and is pressed at all times in the opening direction by means of a spring 27. The click 20 is axially supported by a connecting ring 28 attached with a handle 17b in the front of the cam sleeve 19 and connected integrally to said connecting ring. Reference numeral 29 designates an oil pressure hose joint.

The extruding device having the aforementioned construction is arranged at the tip end of the concrete pole 11 which has been molded in the preceding step as illustrated in FIG. 1, and the handle 17a is brought from the state shown by one-dot chain line to the state shown by solid line, and, as shown in FIG. 3, the flange 12a of the mold frame 12 is engaged with the extruding

device by means of the click 20, then the oil pressure jack 15 is operated and the tip end of the concrete pole 11 is pressed by a rod 15a thereby to protrude the bottom end of the concrete pole 11 out of the bottom end side of the mold frame 12.

As has been mentioned above, in the extruding device according to the present invention, the oil pressure jack 15 and the like are mounted on a freely traveling trolley 16 in a freely vertically adjustable manner, a plurality of clicks 20 engaged with the concrete pole mold frame 12 are attached to said oil pressure jack 15 thereby to fix the concrete pole mold frame 12, the concrete pole 11 is pushed in the direction of the bottom end of the mold frame 12 by the oil pressure jack thereby to carry out preparations for the pulling out in the succeeding step. Hence, it does not require the crane for mold releasing operation, and it is sufficient if only bolts of the mold frame on one side are released, as a result of which the operation becomes simple and safe and its effect in practical use is remarkable.

FIGS. 5, 6 and 7 respectively show one example of a pulling-out device. The concrete pole 11 extruded about 50cm from the mold frame 12 is held at its bottom end 11a by a clamp click 32 attached to a clamp trolley 31 constituting the pulling-out device B. The clamp trolley 31 travels in the direction shown by arrow by a wire 30 driven by a motor (not shown) while being guided by monorail type guide rails 33 and 33', but, upon this occasion, the concrete pole bottom end 11a is held further stronger by the toggle effect. More specifically, the intermediate part of the clamp click 32 is pinned to an arm 31a on the clamp trolley 31, and further the clamp trolley 31 and the clamp click 32 are connected to each other at two points through oblique links 31b and 31c, and hence the forward end of the clamp click 32 tends to close with respect to the travel of the clamp trolley in the direction shown by arrow. Thus, the concrete pole 11 is pulled up to a predetermined position on the roller 14.

A limit switch (not shown) acts to operate a lifting jack 34 for transference at a predetermined position during the travel of the clamp trolley 31, and the V block 13 at the forward end is caused to descend. By the descent of said V block 13 the lower surface of the concrete pole 11 is made horizontal surface, and hence it is placed on the roller disposed on a horizontal surface without any trouble and smoothly.

Reference numeral 35 designates a handle for vertically adjusting the clamp click 32 in correspondence to the height of the concrete pole 11, said handle being attached to the clamp trolley 31.

On the other hand, the mold frame 11 which has been emptied causes the lifting jack 34 for transference to operate, and inclines the V block 13 to roll it to a transfer base 36.

FIGS. 8 and 9 show the second example embodying the pulling-out device according to the present invention. A clamp trolley 42 is fitted to an endless chain 37, and the endless chain 37 is driven by a brake motor 38 thereby to shift the clamp trolley 42 to a position shown by solid line on a parallel rail 41. At this position the bottom end 11a of the concrete pole 11 is held by clamp click 39 axially supported in a freely oscillating manner, and when the clamp trolley 42 is returned to a position shown by one-dot chain line, the concrete pole 11 is pulled out of the mold frame. The concrete pole 11, during its pulling-out step, abuts against a limit

switch (not shown), and the product supporting jack 40 at the tip end part is lifted and the concrete pole is supported by the horizontal surface at its lower surface. When the concrete pole 11 has been transferred to a

predetermined position (by the clamp trolley 42 to a position shown by one-dot chain line), the clamp click 39 is hoisted by a crane (not shown) to be shifted to the succeeding step and the product supporting jack 40 is caused to descend, and restored to the original position.

As has been mentioned above, the pulling-out device according to the present invention can perform the mold releasing operation safely by an extremely simple step, and the operation can be carried out rapidly and automatically.

Furthermore, the present invention is not limited to the aforementioned examples, but for instance, the chuck at the bottom end of the concrete pole can be replaced by that of an oil pressure method or the like, and guiding method can be replaced by other method.

We claim:

1. Apparatus for separating a concrete pole from a mold frame comprising:

vertically adjustable horizontally disposed means for supporting said mold frame and said concrete pole;

means disposed at one end of said mold frame for extruding said concrete pole from said mold frame a predetermined distance;

a plurality of fixed roller support means for facilitating the longitudinal movement of said concrete pole when said concrete pole is separated from said mold frame;

horizontally movable means disposed at the other end of said mold including means for externally gripping said extruded pole and extracting said pole from said mold onto said fixed roller support means; and

means for vertically adjusting said vertically adjustable means for vertically aligning said vertically adjustable means with said roller means whereby said extracted pole may be placed upon said fixed roller support means.

2. Apparatus for separating a concrete pole from a mold frame including an extracting device comprising:

a hydraulic jack having movable ram means for engaging and extruding said pole from said mold frame a predetermined distance;

a plurality of gripper means disposed about said jack for gripping a flanged portion of said mold frame;

spring means respectively associated with each of said gripper means for biasing said gripper means to an open position whereby said gripper means may be disposed about said flanged portion of said mold frame; and

rotatable cam means disposed about said jack for biasing said gripper means to a closed position whereupon said gripper means may grip said flanged portion of said mold frame.

3. Apparatus for separating a concrete pole from a mold frame including an extracting device comprising:

a trolley movable upon guide rail means;

clamping means pivotably secured to said trolley for externally gripping a portion of said pole which has been exposed from said mold frame; motor driven cable means secured to said trolley for moving said trolley; and toggle means interconnecting said clamping means

and said trolley whereupon said clamping means are biased toward a closed, clamping position when said motor driven cable means moves said trolley in a direction so as to extract said pole from said mold frame.
